PENNSYLVANIA, ASSIGNEES TO A. H. BALLIET CORPORATION, OF ALLENTOWN,
PENNSYLVANIA, A CORPORATION OF PENNSYLVANIA

LID-WRAPPING MACHINE

Application filed June 16, 1927. Serial No. 199,230.

Our invention relates to mechanism for wrapping lids of cigar boxes.

A purpose of our invention is to provide mechanism adapted to efficient, easy and inexpensive application of wraps to cigar box lids.

A further purpose is to register the top of a lid of a cigar box with a design upon the outside of a glued lid-wrap while the wrap is on a belt conveyer delivering to a wrapping machine and illumined from below through the material of the conveyer.

In order to avoid having the belt become gradually opaque to the light by reason of gradually accumulating glue from the glue machine, we preferably isolate the section of conveyer at the illumined registry station from the conveyer portion that receives the wraps from the glue machine.

A further purpose is to mount a raised gauge or stop along the lower block of a wrapping machine and to register a lid and wrap with the block against the gauge, using the fingers of the operator to register the ends of the lid flush with the ends of the stop.

A further purpose is to support the pressure exerted by the rear roll of a wrapping machine operating to roll up the turn-up flap across the front of the lid of a cigar box by the pressure of an opposing front roll exerted against a stop gauge rigidly fastened to the lower form along the back of the lid. The gauge is preferably equal in height to the thickness of the lid so that the two rolls are simultaneously respectively in engagement with the front of the lid and the outside of the gauge.

A further purpose is to support the upturned front flap of a cigar box lid by a brush below the roll effecting the turn-up until the turned up flap has been engaged by a turn-in roll.

A further purpose is to effect the long side turn-in along the front of a lid by rolling action, preferably mounting a resiliently downwardly pressed turn-in roll upon the so-called rear corner-lap plate holder bar of a wrapping machine.

A further purpose is to effect the end turn-ins of the lid of a cigar box by rolling action,

preferably mounting resiliently downwardly pressed rolls upon the so-called turn-in plate holders of a wrapping machine.

A further purpose is to eject wrapped cigar box lids from a wrapping machine in a direction away from the operator, preferably passing them directly between finishing rolls. These rolls smooth out unevennesses in the wrap and effect a more intimate contact between the wrap and lid.

Further purposes will appear in the specification and in the claims.

While our invention is well adapted to use with wrapping machines of widely variant types, we have elected to show it embodied upon a Stokes & Smith type of machine for the reasons that our invention is well adapted to this machine, and disclosure upon a well-known machine makes detailed description unnecessary as to many parts that are in themselves not part of our present invention. The United States patent most nearly corresponding with the complete Stokes and Smith machine is patent to Sonneborn, No. 1,646,563, issued October 25, 1927, from whose illustration and description the operation of all of the machine shown, which is not explicitly described herein, may be clearly understood. The embodiment shown is convenient and efficient in operation and illustrates particularly well the principles involved.

Figures 1 and 2 are a fragmentary top plan view and a front elevation, respectively, of conveyer mechanism embodying some portions of our invention.

Figure 3 is a fragmentary broken front elevation of a wrapping machine embodying our invention and showing a portion of the conveyer mechanism of Figures 1 and 2.

Figures 4 to 6 are fragmentary end elevations illustrating different positions of mechanism for turning the front flap of the wraps up and over the bottoms of the lids.

Figures 7 and 8 are fragmentary perspectives of roll turn-in mechanism used by us at the front of the lid.

Figures 9 to 11 are broken front elevations of mechanism for turning the end flaps of

the wraps up and over the bottoms of the lids.

Figures 12 and 13 are perspective views of an end turn-in roll, taken from above and below the roll mechanism, respectively.

Figure 14 is a fragmentary enlarged rear end elevation showing the lid as held to place between upper and lower forms, preparatory to wrapping over the long side of the wrap.

Figure 15 is a fragmentary perspective view showing ejector mechanism for discharging the wrapped lids from the wrapping machine.

Figure 16 is a fragmentary top plan view of ejector mechanism shown in Figure 15.

Figure 17 is a top plan view of a wrap before it has been applied to a lid.

Figures 18 to 27 are diagrammatic perspective and top plan views, arranged in pairs, illustrating different steps of the wrapping operation.

Figures 18 and 19 show the wrap after the lid has been applied to it but before the flaps have been turned up.

Figures 20 and 21 show the wrap and lid after the front flap has been turned up.

Figures 22 and 23 show the front flap turned in.

Figures 24 and 25 show the end flaps turned up but not turned in.

Figures 26 and 27 show the wrap as in place after the end flaps have been turned in.

Figure 28 is a fragmentary perspective view of wringer mechanism to which the ejected lids pass after the wrapping operation is complete.

Figure 29 is a side elevation of Figure 28 with additional structure.

Figure 30 is a fragmentary detailed elevation to enlarged scale omitting parts to show the relation between mechanism illustrated in Figures 3 to 6.

Figures 31 and 32 are a fragmentary enlarged top plan view and a section of it upon line 31—31 illustrating the registration of the lids with the lower form.

Figure 33 is a diagrammatic chart showing the cycle of operation.

General layout

The general layout of the mechanism is shown in Figures 1, 2 and 3; a desirable form of wrap is shown in Figure 17 and different steps of wrapping operation are shown in Figures 18 to 27.

Referring to Figures 17 to 27, the wraps are applied to the tops of the lids and preferably do not extend quite to the back edges at the hinges, being cut away or terminating short of the edge. They lap over to the lid bottoms along the fronts and ends.

A narrow strip on the top of the lid adjacent the back edge is left uncovered for an overlap portion of a linen hinge applied sub-

sequently to the wrapping of the lid, and not part of the present invention.

The wrap (Figure 17) is preferably provided with edge lines for registry with the front and end edges of the top of the lid, and the lids are applied to the successive wraps at a registry station upon the conveyer, strong illumination beneath the conveyer making visible the registry lines in order to facilitate placing the lids in proper registry with the wraps.

At the wrapping machine the front flaps still down in Figures 18 and 19, are first turned up as shown in Figures 20 and 21, then turned in over the bottom of the lid as shown in Figures 22 and 23. After this the ends are turned up as shown in Figures 24 and 25 and then turned in as shown in Figures 26 and 27.

Figures 1 and 2 show conveying mechanism for delivering the lids and wraps to the wrapping machine. This mechanism is normally operated by the mechanism feeding wraps to any suitable glue machine, not shown, which is preferably in turn controlled by or synchronized to the operation of the wrapping machine (Figure 3).

The feed cylinder of the glue machine, for example, is suitably connected to make one rotation for each vertical reciprocation of the upper and lower plungers of the wrapping machine, each such reciprocation completing the wrapping cycle for one lid.

The glue machine and its feed mechanism are not shown and we have not shown the control from the wrapping machine. They are in themselves not part of the present invention, which relates to novel operations and mechanisms to be embodied partly in a conveyer and partly in a wrapping machine at the delivery end of the conveyer.

The illustrations of the conveyer and wrapping machine, with which we show our invention embodied, are intended as conventional illustrations for any conveyer and any wrapping machine to which our invention is adapted to be applied.

The conveyer and the registry station thereof (Figures 1, 2 and 3)

The belt conveyer 40 receives the wraps 41 from a suitable glue machine, not shown, and moves forward with intermittent steps that are of the same length and of a length that is predetermined and usually adjustable. Each time that the wrapping machine 42 completes its wrapping cycle, a new wrap is delivered glue side up from the glue machine to the belt conveyer, and the conveyer makes one of its forward movements advancing the wraps already on the conveyer toward the wrapping machine.

The successive wraps are thus placed glue side up along the conveyer at uniform intervals between the gluing and wrapping ma-

chines and come to rest successively at the same definite positions or stations between the two machines.

We register the tops of the lids on the glued surfaces of the successive wraps at one of these stations. At this registry station 43 we support a light-transmitting plate 44, preferably glass, beneath the belt conveyer and place a strong light 45 beneath the plate, the plate and light both being carried upon a frame structure 46 that is in turn supported by, and preferably adjustable along side rails 47 of the conveyer.

The upper surface of the glass is even with the upper surface of the frame, the two surfaces presenting a firm horizontal support to the bottom of the belt conveyer so that the belt may present even support to the successive wraps during the application 20 of the lids, and the frame and glass should be high enough to insure a section of flat belt over the whole surface of the glass.

In practice the upper surface of the plate and frame is preferably raised somewhat 25 with respect to the opposite ends of the conveyer, as shown in Figure 2.

The wraps (Figure 17) preferably carry a heavy printed line 48 for registry around the front and end edges of the top of the lids 30 49.

The wrap has no flap at its rear side in that it must leave the rear edge of the lid and desirably also a narrow strip along the top of the lid adjacent the rear edge uncovered for the application of a linen hinge. This hinge usually does not extend the full 35 length of the lid and the rear of wrap is shown cut away for the hinge at 41'. The hinge and a finishing strip over it are applied subsequently to the wrapping operation of the present invention.

The lines 48 become visible when the wraps reach the registry plate, due to the strong light beneath the plate, and make it very easy for an operator to secure exact 45 registry of the lids upon the successive wraps. The operator places the lids top side down so that their outer edges register with the lines on the wrap.

It is old to register a box upon a glued wrap while the wrap is lying upon a glass plate with a light beneath the plate. Hitherto, however, this has been done after the wrap has been removed from its belt conveyer. We avoid a removal from the conveyer by passing the conveyer over the glass making the light sufficiently strong to shine through the material of the conveyer and making the conveyer of material that will 55 permit this.

We have found that a strong light will satisfactorily shine through a conveyer of canvas or like material if the conveyer be reasonably free from glue. The conveyer 60 shown comprises two sections to operate as a

unit, connected by chain and sprockets 50. The first section 51 receives the successive wraps from a glue machine, not shown.

In practice we have found that the belt 51 becomes gradually coated with glue by 65 reason of glue dropping from wrap-stripping mechanism at the glue machine and that this glue coating makes the conveyer become gradually opaque.

The conveyer can be cleaned at intervals 70 by wire brushes so as to be fully operative for registration over the light but we have found it more desirable to register upon a belt 52 kept free from glue by isolation from the belt 51.

The belts of the adjoining sections pass over horizontal parallel rolls 53 that keep the adjoining belts 51 and 52 from contact yet are sufficiently close to avoid danger of any of the wraps failing to pass from section to section.

The second belt 52 receives the wraps from the first belt and brings them successively to rest over the light and registry plate 44 where an operator registers the lids and wraps as stated.

The light and registry plate can be placed under the main belt but it is preferable to isolate the portion of the conveyer at the registry station as already stated.

We have found that it is desirable to surround the two conveyers with a string or narrow tape 54 which travels at the same speed as the conveyers and bridges the space between the conveyers, thus avoiding any danger of glued wraps failing to pass from the first to the second conveyer.

Wrapping machine

The wrapping machine with which our invention is embodied is shown in Figure 3 which is a broken elevation partly in section and with many parts removed from the operator's side of the machine. The conveyer section 52 is broken away in front of the operating mechanism of the wrapping machine at the delivery station 55 (Figures 1 and 2) of the conveyer which is in front of the vertically reciprocating plungers of the wrapping machine.

In the wrapping machine, a driving pulley 56 mounted upon the shaft 57 is driven continuously in any suitable way and has clutch connection at 58 with a sleeve 59. This sleeve surrounds the drive shaft and carries a worm 60 in continuous mesh with a gear 61 upon the lower end of a cam shaft 62.

All of the wrapping movements of the machine are operated through the medium of cams upon this cam shaft which also controls the feed of wraps to the glue machine as already described. The machine shown is of well-known type used in wrapping paper boxes and the like.

The upper plunger block 63 is carried upon the bottom of a plunger 64 and the plunger

is adapted to reciprocate vertically, being guided in suitable stationary guide portions 65 of the frame of the machine.

The plunger 64 is positioned vertically by a cam groove 66 around a drum 67 upon the upper end of the cam shaft. The connection is made by means of a roller 68 upon a rocker lever 69 and a link 70 between the lever and the plunger. The lever is pivoted at 71 in a suitable fixed bearing 72.

A lower block 73 is mounted upon the head 74 of the wrapping machine. This head is a well-known standard member of the wrapping machine. It is resiliently pressed upwardly toward its upper position by a spring 75 and presents the lower block spaced beneath the upper block initially a sufficient distance from the upper block for easy insertion of a lid and wrap upon the lower block.

20 The wrapping operations take place during the downward travel of the upper block after it has engaged the lid upon the lower block which moves downwardly when the upper block moves down and subsequently rises as 25 the upper block rises until the block again reaches its upper position where it comes against a suitable stop and ceases to follow the upper block upwardly. The upper block continues in its upward motion after the 30 wrapping cycle has been completed and finally stops in its initial position.

The successive lids are delivered top side down in front of the lower block at which point they are successively picked up by the 35 operator and placed upon the lower block preparatory to wrapping.

In transferring the lid with its wrap glued to its upper side (now turned down) an operator conveniently lifts the lid by holding its 40 ends between two fingers as illustrated in Figures 31 and 32, the end flaps of the wrap at this time extending outwardly beneath the fingers of the operator.

The operator after raising the lid and wrap 45 and placing it on the lower block pulls the lid forwardly against a raised gauge 76 along the front of the block, using the ends 77 of the raised portion to gauge the longitudinal position of the lid. At each end the corresponding 50 finger simultaneously overlaps the raised portion of the block and the adjacent end portion of the lid.

After the lid and wrap have been put to place on the block the operator starts the 55 wrapping cycle by moving a suitable lever 78 of the machine.

The upper block presents a surface considerably smaller than that of the lid while the lower block presents an upper surface having 60 outer edges registering with the outer edges of the top of the lid (now down). The upper block descends upon the lid registered upon the lower block and clamps it to place between the upper and lower blocks against the retractive force of the spring 75.

The successive wrapping operations are shown in Figures 18 to 27.

The front flap 79 is first turned up while passing the lid and blocks between the usual rolls 80 and 81, (Figures 4 and 5), the front 70 flap being presented to the rear side of the machine.

The front roll 81 rolls up the front 82 of the lower block and the outside of the gauge 76 while the rear roll rolls up the rear 83 75 of the lower block and the front flap 79. In this way the pressure of the rear roll upon the rear of the block is balanced by a corresponding equal and opposite pressure of the front roll.

The height of the gauge 76 is preferably the same as the thickness of the lid in order that the two rolls may have the same simultaneous periods of engagement.

We dispense with the wiping brushes normally carried above front and rear rolls but mount a brush 84 somewhat below the rear roll, preferably upon the holder 85 of the rear roll.

This brush 84 engages the upturned front 90 flap after the flap has passed down from the rear roll and maintains engagement therewith until the flap is engaged by a turn-in roll 86.

We mount a turn-in member for the front 95 flap as a roll 86 upon the corner-lap plate holder bar of the prior art, resiliently pressing this roll downwardly.

The blocks and lid after moving downwardly between the front and rear rolls 80 100 and 81 come to rest in the position shown in Figure 6 and at which position the corner-lap plate holder bar of the prior art carrying the turn-in roll 86 moves inwardly to effect turn in, rolling the upper portion of the 105 turn up lap 79 down upon the bottom of the lid.

After the turn-in roll mounted upon the corner-lap plate holder bar has moved in and while it is still at its inner position the 110 blocks carrying the lid and wrap again move downwardly under the action of the cam 66, roller 68, rocker arm 69 and link 70. This downward movement carries the block and lid between the end turn-up brushes 87 and 115 the end turn-up rolls 88, both of the prior art, to come to rest in position for the operation of the end turn-in.

We mount end turn-in rolls 89 upon the end turn-in plate holders 90 of the prior art. 120 These rolls move inwardly and again outwardly to effect a rolling end turn-in while the blocks are in their second position of rest.

After the end turn-in operation is complete 125 and the turn-in rolls have moved back out of the way, the blocks may at once start to rise. In the machine under illustration however, the blocks and wrapped lid may move further down before beginning to rise for 130

adaptations to box wrapping operations not used in the present invention.

When rising, the upper block is lifted by the upper plunger and the lower block follows under the upward pressure of the spring 75 until it reaches its upper position at which point it ceases to rise, the upper block moving on up out of the way leaving the wrapped lid upon the lower block.

- 10 Before the cycle is complete, and after the upper block has moved up out of the way 25 ejector mechanism 91 (Figures 15 and 16) striking through a central recess 92 in the gauge portion of the lower block, knocks the wrapped lid rearwardly to pass between finishing rolls 93 and 93' that operate somewhat like a wringing machine; and which smooth out any unevennesses of the wrap and bring the wrap and lid into more perfect and 20 uniform contact.

Front turn-in (Figures 3 to 8)

The front turn-in mechanism is an important feature of our invention and is shown 25 as a roll 86 resiliently pressing downward. The roll mechanism is mounted upon the so-called rear corner-lap plate holder bar 94 of the wrapping machine of the prior art. The front corner-lap plate holder bar of 30 the prior art is not used and not shown.

In the wrapping machine of the prior art a rocking member 95 (Figure 3) carries a suitable roller 96 operating in a cam groove 97 to effect the inward and outward movements of the corner-lap plate holder bars. The rocker 95 is linked to a secondary rocking member 98 that is in turn linked at 99 (Figures 3 to 8 and 30) to a sliding member 100 carrying the bar 94 carrying our front 40 turn-in mechanism.

The sliding member 100 comprises horizontally spaced rods 101 and 102 rearwardly extending from a plate 103 that is rigidly fastened to the corner-lap plate holder bar. The rearwardly extending rods have sliding bearing through suitable perforated lugs 104 of which one only is shown.

The link 99 to the rocker member is pivotally connected at 105 to a cross member 106 between the rods 101 and 102. The cross member is rigidly fastened to these rods and adjustable longitudinally along them, as in the prior art.

55 Our front turn-in mechanism comprises the roll 86 journaled in the ends of the forwardly extending arms 107 of spaced bell crank members 108 which are pivoted at 109 to blocks 110 fastened to the rear corner-lap plate holder bar.

60 Downwardly extending arms 111 of the bell cranks stop against the respective forward faces of the blocks and are spring-pressed inwardly toward engagement with

these faces by individual springs 112 stretched between suitable anchors 113 and 114 respectively upon the blocks and lower portions of the arms.

Mounting the turn-in roll mechanism upon 70 the corner-lap plate holder bar of the prior art is new and particularly advantageous.

End turn-in mechanism (Figures 3 and 9 to 13)

We effect the end turn-ins by resiliently downwardly pressing rolls mounted upon the end turn-in plate holders of the prior art.

In the machine of the prior art the turn-ins have been moved inwardly and outwardly by means of cam 115, roller 116, rocker lever 117 pivoted at 118 to a fixed part of the machine and linked at 119 to vertically reciprocate a central sleeve 120 surrounding the lower portion of the lower plunger 121.

The sleeve 120 has oppositely extending arms 122 which carry vertical rods 123 linked at 124 to rocker arms 125 that are in turn linked at 126 to the turn-in plate holders 127 of the prior art.

The horizontal reciprocation of the turn-in mechanism of the prior art is thus effected by the vertical up and down movements of the central sleeve 120 which is in turn effected by the rocker arm 117 and cam 115.

The plate holders 127 comprise slides having horizontally spaced rods 128 extending outwardly from blocks 129 to which we fasten our end turn-in roll mechanisms.

The block 129 is pivotally connected at 130 to the link 126 of the rocker 125 and the rods operate in suitable bearings, not shown, but generally similar to the bearings 104 of the front turn-in mechanism (Figures 4 to 6).

Our end turn-in rolls have journal support 105 at the ends in lever members 131 which are pivoted at 132 to a supporting block 133 fastened at 134 to the holder 129 of the prior art. The outwardly extending arms 135 of the levers 131 are recessed to receive stop pins 136 which project outwardly from the ends of the blocks 133 (Figures 12 and 13) and are spring-pressed to contact with these pins by flat springs 137 fastened upon the bottom of the blocks (Figure 13).

The new feature of this mechanism comprises the advantageous roll mechanism mounted upon the turn-in plate holders of the prior art.

The end turn-in operations take place at the second position of rest and complete the wrapping operation at the wrapping machine. The wrapper machine of the prior art is usually built to give the plungers a short additional downward movement and we prefer to let the machine have this unnecessary further downward travel of the plungers for the sake of the resultant adaptation of the machine to box wrapping.

Ejector mechanism (Figures 3, 15, 16 and 29)

After the end turn-in operations have been completed and with or without additional downward movement of the plungers, the 5 plungers rise until the lower block is left in its initial position, the wrapped lid lying on the lower block back of the gauge 76 and the upper block moving on up out of the way.

Ejector mechanism striking through the recess 92 in the front gauge 76 knocks the wrapped lid rearwardly into a position at which it is taken hold of by the finishing rolls 93 and 93' and passed between these 10 rolls.

15 We mount a rocker 141 upon a vertical pivot 142 upon a fixed part 143 of the machine in front of the lower block and link one end of this rocker to the ejector plunger 144 at 145 and the other end at 146 to the head 147 20 of the ejector of the prior art which has a spring-release governed by a cam upon the main cam shaft.

We use the same spring release for ejecting the lid that was used in the prior art but 25 eject rearwardly instead of laterally.

The ejector plunger 144 operates in a suitable guide 148 in line with the recess 92 of the gauge.

30 We find if the blows of ejector plunger are either too hard or too light the lids will not be taken hold of by the finishing rolls.

As the wrapping machine operates upon variant types of lids we find it desirable to 35 make the strength of blow struck by the ejector plunger adjustable and may do this by providing a succession of perforations 149 to receive the pivot connection 150 between the plunger 144 and the link member 145.

40 The lid ejection is in a direction away from the operator because we mount the finishing rolls at the far side of the machine. We thus eject the lid in a direction at right-angles to the line of the operation of the ejector plunger of the prior art.

The finishing rolls (Figures 3, 28, 29, and 30)

These operate to smooth out any unevenesses in the wrap left by the wrapping machine and to make a more perfect and intimate 50 contact between the glued wrap and the lid.

The finishing rolls 93 and 93' normally 55 revolve continuously and may be suitably driven by gearing from the drive shaft 67 of the machine, or, as illustrated in Figure 3, may be provided with a separate motor drive.

In Figure 3 the shaft 153 of the lower roll 60 93 carries a pulley 154 which is connected by belt 155, pulley 156, shaft 157, pulley 158, belt 159 and pulley 160 to the shaft of an auxiliary motor 161.

The lower roll is journaled in fixed bearings 162 and the upper roll is journaled in 65 bearings 163 that are spring-pressed downwardly at 164 to maintain friction contact

between the rolls, the lower roll driving the upper roll by friction, the upper roll rotating as an idler only by reason of engagement with its mate, or by reason of engagement with a finished lid passing through between the rolls. Optionally the rolls are geared together.

The rolls deliver the finished lids away from the machine to a suitable inclined chute 165.

Cycle of operation

A desirable cycle of operation when the invention is embodied upon a wrapping machine of the type shown is indicated diagrammatically in Figure 33.

Some of the operations indicated upon the cycle may be considerably modified if a different type of wrapping machine is used, and some of the movements indicated are unnecessary during the wrapping operation of the invention, the movements being taken from a well-known machine of the prior art, and being in some instances such as to adapt the machine of the prior art to operations foreign to the present invention.

Vertical ordinates on this chart represent simultaneous positions of the respective parts throughout a single cycle, the common abscissæ representing time and the respective parts being shown by suitable notations on the different curve lines which are also lettered for greater convenience of reference. The different movements are away from and back to initial positions, some of these movements being down and up and others horizontally inward toward the lid and backward from the lid.

Preparatory to the cycle an operator places a lid from the conveyer on to the lower block of the wrapping machine. This lid is top side down upon the conveyor and has a wrap glued to its top, now down.

An operator preferably picks up the lid by two fingers at the opposite ends of the lid above the extending end flaps lays it upon the lower block, draws it forward into contact with the raised portion 76 of the block (a registry gauge) and secures longitudinal registry by simultaneously passing the fingers from the ends of the lid across the ends of the raised gauge.

The clutch of the wrapping machine is then released at 170. The upper block now some distance above the lower block, moves down until at the point 171 it engages the upwardly presented bottom of the lid upon the lower block, clamping the lid between the opposing rubber covered faces of the upper and lower blocks, and starting the lid and lower block upon its downward travel against the upward force of the spring 75, to ultimately come to rest after passing between the front and rear rolls 81 and 80 respectively at the point 172.

130

In the passage between the front and rear rolls (Figure 4) the rearwardly projecting front flap is rolled up the front of the lid by the rear roll, the resilient pressure of this roll 5 against the lid being balanced by an equal and opposite resilient pressure exerted by the front roll which rolls up the outside of the gauge 76 at the same time that the rear roll is turning up the front flap.

10 When the upper and lower blocks come to rest at the point 172 both the rear roll 80 and the supporting brush 86 are above the upper edge of the turned up front flap 79 and the front turn-in roll 86 mounted upon the corner-lap plate holder bar of the prior art is in position to move inwardly to effect turn-in. The supporting brush 84 has maintained contact however with the front flap until the flap 15 is in position to be supported by the turn-in roll 86 (Figure 5).

At the point 173 the turn-in roll 86 mounted upon the rear corner-lap plate holder bar of the prior art begins to move inwardly (Figure 6) to effect turn-in and turn-in is 20 complete at or before the point 174 at which the turn-in roll is at its innermost position, before the next downward movement of the blocks.

At the point 175 the upper and lower blocks 25 begin to travel downwardly to pass between the end turn-up brushes 87 and end turn-up rolls 88 (Figures 9 and 10) which turn up the end flaps of the wrap, the blocks coming again to rest at the point 176.

30 The end turn-in rolls with the blocks at rest move inwardly to effect end turn-ins between the points 177 and 178 (Figure 11) and move again outwardly between the points 179 and 180.

35 The downward travel of the blocks shown between the points 181 and 182, as well as the subsequent movements of the turn-in rolls indicated along the curve E are for purposes foreign to the present invention, also the period of rest between the points 182 and 183 40 before the blocks begin to move upwardly is to allow time for operations foreign to the present invention.

45 At the point 183 the blocks begin to rise, the lower block having reached its upper position at the point 184.

50 Between the points 184 and 185 the lower block is stationary and the upper block is rising reaching its upmost position at the latter point.

55 At a point 186 the kick-off (lid ejection) takes place the time of the kick-off being sufficiently after the point 184 to permit the upper block to be out of the way. The kick-off or ejector mechanism delivers the wrapped lid to the finishing rolls. The clutch opens at 187 and the cycle is complete.

60 While we have illustrated our invention applied to wrapping cigar box lids it will be noted that various features of our inven-

tion are suited to operate upon the lids of other boxes than cigar boxes and some of them apply generally in the box-wrapping art.

In view of our invention and disclosure 70 variations and modifications to meet individual whim or particular need will doubtless become evident to others skilled in the art, to obtain all or part of the benefits of our invention without copying the structure shown 75 and we, therefore, claim all such in so far as they fall within the reasonable spirit and scope of our invention.

Having thus described our invention, what we claim as new and desire to secure by Letters Patent is:—

1. In a lid-wrapping machine, an upper plunger, a lower plunger in line therewith resiliently supported, a block upon the lower plunger adapted to receive the lid and to be 85 pressed downwardly along with the plunger by downward movement of the upper plunger, and a gauge secured to the lower block adjacent to the position of the rear of the lid and adapted to register at its ends with the ends of the lid for manual determination of the position of the lid.

2. In a lid-wrapping machine an upper plunger, a lower plunger in line therewith resiliently supported, a lower block upon the 90 lower plunger adapted to receive the lid and to be pressed downwardly along with the lower plunger by movement of the upper plunger and a gauge extending above the block to a height corresponding approximately with the thickness of the lid and having a length approximately equal to that of the lid whereby the rear of the lid may be 95 roller-supported through the roller support of the gauge while the front flap of the wrap 100 is being rolled up.

3. In a machine for wrapping lids, a downwardly movable upper plunger and block, a resiliently supported lower plunger and form, a front flap turn-up roller initially 110 located beneath the upper level of the lower form, a brush mounted below the roll in position to support the flap after it has been turned up, and a turn-in roll and connections adapted to engage the flap while it is 115 supported by the brush and to roll it in over the bottom of the lid.

4. In a machine for wrapping lids, a downwardly movable upper plunger and block, a resiliently supported lower plunger and form 120 aligned therewith, a gauge on the lower form along the front thereof having height and length respectively equal to the thickness and length of the lid, rollers respectively in front and rear of the form and initially below the form, the front roller being adapted to roll up the front of the gauge while the rear roller is 125 rolling up the front flap of the lid.

5. In a machine for wrapping lids, a downwardly movable upper plunger and block, a 130

resiliently supported lower plunger and form, a front flap turn-up device, and a transversely movable downwardly pressing front turn-in roller adapted to turn-in the turned up front flap and roll it on to the bottom of the lid.

6. In a wrapping machine having a holding bar, a downwardly movable upper plunger and form, a resiliently supported lower plunger and form, a front flap turn-up device and a roller turn-in device mounted upon the corner lap plate holder bar and adapted to roll down the front lap on to the bottom of the lid.

15 7. In a machine for wrapping lids, a downwardly movable upper plunger and block, a resiliently supported lower plunger and form, downwardly pressing end turn-in rolls, and turn-in holder mechanism adapted to carry the rolls to roll down the end flaps of a wrap upon the bottom of the lid.

20 8. In a machine for wrapping lids, a downwardly movable upper plunger and block, a resiliently supported lower plunger and form, downwardly pressing end turn-in rolls, and turn-in holder mechanism adapted to reciprocate the rolls upon the ends of the bottom of the lid to roll down the end flaps of a wrap upon the bottom of the lid.

25 9. In a machine for wrapping lids, a downwardly movable upper plunger and form, a resiliently supported lower plunger and form, end turn-in rolls mounted to bear resiliently downwardly upon the bottom of the lid and turn-in plate holder supports for the end turn-in rolls.

30 10. In a lid-wrapping machine, a pair of squeeze rolls adapted to squeeze a wrap into tight union with the lid, an ejector for feeding the lids from the wrapping machine to the rolls and an adjustment in the range of the ejector.

35 11. A lid-wrapping machine, an ejector pin and connections therefor, and lever mechanism connected with the ejecting pin for throwing the lids in ejection in a direction substantially in the direction of motion of the ejecting pin.
